J. F. GELNAW,
IDENTIFICATION AND CODING SYSTEM,
APPLICATION FILED MAY 5, 1921.

Patented July 25, 1922.

UNITED STATES PATENT OFFICE.

JOHN F. GELNAW, OF CLEVELAND, OHIO.

IDENTIFICATION AND CODING SYSTEM.

1,423,763.

Specification of Letters Patent. Patented July 25, 1922.

Application filed May 5, 1921. Serial No. 466,968.

To all whom it may concern:

Be it known that I, JOHN F. GELNAW, a citizen of the United States of America, residing at Cleveland, in the county of 5 Cuyahoga and State of Ohio, have invented certain new and useful Improvements in Identification and Coding Systems, of which the following is a specification.

My invention relates to improvements in 10 an identification system, the object of which is the designation or marking of articles, so that they may be readily and positively identified, regardless of any fraudulent attempt to defeat the system and its purposes. 15 My invention will be explained in connection with an interrelated scheme of coding and marking automobiles for the purpose of discouraging theft, and with the possibility of positively identifying any stolen car. 20 However, it should be understood at the outset that my invention is not necessarily related to and limited by the exemplification herein set forth and explained.

My improved system has as its ground 25 work a definite coded scheme of marking in obscure places any article or mechanism, so that the eradication of one or more of the plurality of such marks will almost as readily indicate by its position or positions, the 30 particular identified article. Thus with an automobile marked in a distinctive but obscure manner in half a dozen out of several times that number of coded positions; those positions being known only to the identifying agency, a very brief inspection of the 35 automobile will disclose either the marks identifying it, which preferably are stamped into the metal, or an obliteration of any mark or marks fraudulently discovered and 40 tampered with. Thus, with the practical certainty of future identification, coupled with the uncertainty of discovering all of the numerous identifying marks, there remains small incentive to steal an automobile, 45 or indeed any other article lending itself to my system, which has been suitably identified.

Briefly explaining my improvement, preliminary to its explicit and selected use, I 50 may say that the article to be identified is first carefully charted and numerous positions of marking are selected, which preferably are more or less obscure, and which may correspond in number to the letters of 55 the alphabet. Other positions similarly are charted corresponding to the digits; all be-

ing secretly recorded at a central office and any branch offices that may be established. A code symbol and a number of several figures are then assigned to each identified article; the code preferably being short and containing both letters and figures, as "X3B." The number is then coded into corresponding letters of the alphabet, and the symbol, "X3B" is stamped with a steel 60 stamp upon those parts of the article which are indicated in the chart by the corresponding letters and also the figure. As a result, none but the home office is in position to discover all of the positions in which the article is marked, and if the marks are small 65 and obscurely stamped upon the article, such as an automobile, it would be a matter of great uncertainty whether any stranger could find and eradicate such marks. Moreover, the filing or resurfacing of the metal 70 locally where any mark has been stamped, at once serves to place thereon a substitute identification in one or more of the selected 75 positions.

If desired, I may also couple with the above a different type of marking, such as an obscurely placed and concealed drill hole, or holes of small but defined size, so that the coded marking is supplemented by a 80 different and distinctive symbol.

Although the nature of my invention does not well lend itself to illustration, I may make reference to the accompanying drawings by way of graphic showing, wherein:

Fig. 1 is a plan view in outline of the frame of an automobile whereon the charting for identification is indicated.

Fig. 2 is a fragmentary view in section and perspective of a metal member marked 95 with the symbol "D2A" by means of a steel stamp for the purposes of identifying and coding any mechanical structure, and

Fig. 3 is a sectional view showing the secret drill point hole X, employed as an 100 additional identification when properly positioned.

The primary use to which I propose to make of my invention, as indicated, is the protection of automobiles from theft and in 105 order to accomplish this it is necessary to have a central office, preferably associated with a large number of branch offices at which the records are duplicated and by which the automobiles are marked for identification. It is quite essential that the 110 system of marking shall be definite, indi-

vidual and preferably obscure. In order to accomplish this I have devised a typical coding system which affords a wide range of complex individual designations. The 5 code affords the advantage of protecting the system from general knowledge, both by the public and by the minor employees within the central and branch offices.

Each make of automobile will be separately charted for identifying markings in a relatively large number of positions. This permits the repetition of a simple code symbol for each make of car, or even for each type of car, if desired. For example, we 10 may select the "North Pole" automobile and chart thereon some twenty-six locations corresponding to the letters of the alphabet, upon the chassis and record them thus:

A—Rear spring front hanger, bottom 20 (left side).

B—Rear spring front hanger, bottom (right side).

C—Third cross member, rear, 3" from left side.

25 D—Third cross member, rear, 3" from right side.

This chart will be completed throughout the alphabet, preferably selecting the locations in semi-concealed positions and on un-machined parts which may, however, readily be reached for applying a symbol or character with a steel stamp. Preferably a plurality of series should be adopted, in order to increase the practical range of individual marking.

Accordingly, another series of positions may be selected on the motor, numbered from 0 to 9 inclusive, as:

1—Low and reverse speed gear shifter 40 finger.

2—Intermediate and high gear shifter finger.

3—Lower crank case 6" forward of drain plug.

45 4—Cylinder block between first and second plugs.

This chart will be completed for the six remaining digits, as above explained, so that there will be two series of symbols for completing a marking code for the "North Pole" automobile or for any given model thereof. Obviously another alphabetical series, or a second numerical series might be charted for the body or for the running 50 gear, for example, but the above is sufficiently typical for affording a very wide range of individual marking.

Figure 1 graphically illustrates the specific points for identification upon the automobile as lettered and numbered above, together with other points for additional coded markings, which are not necessary further to identify in explaining my invention.

From the above a letter and figure code 65 is now prepared involving all of the different possible combinations. This may be a two-character code, as "A1", "A2", "A3", etc., but for wider range of marking, I preferably add a third character, such as "A1X", 70 "A2X", or "B1Y", "C2J", "D3M", etc. The three character arrangement will afford some thousands of possible combinations, yet permit of the use of a small and inconspicuous designating symbol. The invention, of course, does not concern itself with any particular coding system, of which many are known, or may readily be devised, but the above will explain how the interrelation of two coding series may be used with 80 advantage to increase the range of individual designation for automobiles, as will be further explained concretely.

Assuming that a "North Pole" model is to be marked for identification, the motor 85 number of which is "1684372", and to which the code symbol "D2A" is assigned, this motor number will be applied to the first series of chassis marking by making the numerical series start with "D" thus:

D	E	F	G	H	I	J	K	L	M
1	2	3	4	5	6	7	8	9	0

Transposing the above motor number into the alphabetical code, we have:

I	6	8	4	3	7	2	95
D	I	K	G	F	J	E	

This immediately indicates the seven out of the twenty-six positions upon which the symbol "D2A" will be stamped upon the chassis of the particular "North Pole" automobile, while the "2" directly indicates that the same symbol will be stamped in the second position or "intermediate and high gear shifter finger" upon the motor. Thus we have provided for some eight coded positions at which the individual symbol for the car is to be obscurely applied.

One of the stamped symbols "D2A" as applied to the chassis of the automobile, or to any other mechanical structure, indeed, is shown in Fig. 2 of the drawings.

If, through repetition of too many digits, as "1.222.221", the motor number is not adapted for the coding designation, it is obvious that an arbitrary number may be assigned to the car for similar use in designation, or this may be directly interpreted in terms of the alphabetical code, if less secrecy as to the system of marking is found desirable.

120 Thus, assuming that the latter number is to be coded for an inapplicable motor number, and "J3X" is assigned as the code symbol, the arbitrary number "J-69245" may be also applied to indicate the coding, which 125 preferably selects an arrangement of the digits in their order, but as "J" is included in the number, this will indicate that the

sequential order is broken, with the "J" for the sixth digit, thus:

J	K	L	M	N	O	P	Q	R	S
6	7	8	9	0	1	2	3	4	5

5 From this the arbitrary number will be coded thus:

J	M	P	R	S
6	9	2	4	5

This provision for giving arbitrary numbers possesses the advantage of permitting an inspector positively to reconstruct the number of any stolen automobile upon discovering the marked portions, or their obliteration, merely by reason of the fact that 10 the digits are numerically arranged. It will be noted that fewer positions may be employed.

While it is quite possible that with extremely careful search, all of the marked 20 positions may ultimately be discovered by the thief of an automobile and defaced or obliterated, in doing so he must make a counter mark in the selected position, of almost equal value in identifying the automobile. Moreover, even if he wished to place misleading marks or obliterations, seemingly, in other positions, the thief must 25 know the entire series of positions in order that he may even temporarily deceive an 30 inspector who is fully advised of the system.

It is necessary, of course, to maintain complete records of all the marking positions, coding and individual automobile 35 designations, both at the central or home office and in duplicate, at any branch office at which the data may come under review. For the individual designations, preferably a printed or multigraphed card system is 40 well adapted, and a typical card for the "North Pole" automobile above considered, would read, in part, as follows:

"Owner, *Jack Frost*. Code symbol, *D2A*.
Address, *515 Cold Water Avenue, Kent,*

45 *Ohio*.
Make of car, *North Pole*.

Model, *A*1921*.

Motor number, *1684372*."

The italicized data, it will be understood, 50 is individual to the particular automobile identified and is written or printed on a form card, which normally would contain a great deal more detailed information regarding the machine and its equipment, but 55 which is quite unnecessary for explaining the use of my invention.

As an additional secret mark, the frame 55 may be drilled, say with a $\frac{1}{16}$ " drill at X, three inches from the rear spring support, 60 in common with all "North Pole" automobiles, and the drill hole filled with dust, oil, or otherwise suitably masked, to afford a definite indication that the car has been registered for the above identification system. Quite obviously, all other makes of

automobiles, and, indeed, most manufactured articles, particularly those constructed of metal, very readily lend themselves to the mode of identification set forth.

The marking, as previously indicated, 70 preferably is readily and quickly applied by means of a set of steel characters cutting into the unmachined surface of the metal to an appreciable depth. This, I may term semi-permanent marking, in that although 75 it may be obliterated, ordinary use of the article will not impair the mark in any way. However any adaptable mode or style of marking may be made to answer.

The procedure above set forth, quite obviously entails a minimum cost for marking the articles of manufacture for identification, and this may be accomplished either in the factory, the garage, or by the roadside, if desired. It is important that the 85 marking may be accurately, quickly and cheaply accomplished, and my instructions, if followed, will achieve these results, and contribute materially to the decrease of 90 theft through the concealed mode of identification thereby secured.

Having now described my invention, together with exemplifications of its use, I claim as new and desire to secure by Letters Patent, the following:

1. The herein described method of identifying articles, which consists in charting positions of identification upon said article, assigning a plurality of such positions individual to the article or class of articles, semi-permanently applying an identifying mark to the article in each of said positions, and making record thereof, substantially as set forth.

2. The herein described method of identifying articles, which consists in charting a relatively large number of positions of identification upon a class of articles, recording the same, assigning a smaller number of such positions individual to the article or sub-class 110 of articles, semi-permanently applying a characteristic mark to the article or articles in each of the latter positions, and making record thereof, substantially as set forth.

3. The herein described method of identifying articles, which consists in charting two series of positions of identifications upon a given class of articles, recording the same, assigning positions from each of the series individual to the article or sub-class of articles, semi-permanently applying a coded mark to the article or articles in each of the latter positions, and making record thereof, substantially as set forth.

4. The herein described method of identifying mechanical structures, which consists in selecting and charting a relatively large number of positions of identification upon the typical structure, recording the same, separately assigning a small number of such 130

positions individual to the particular structure or structures to be identified, semi-permanently applying an identifying mark to each structure in the small number of positions individual thereto, and making record thereof, substantially as set forth.

5. The herein described method of identifying mechanical structures, which consists in selecting and charting a relatively large 10 number of positions of identification upon the typical structure in more or less unobserved locations, recording the same, separately assigning a smaller number of such positions individual to the structure or 15 structures to be identified in accordance with a predetermined code, semi-permanently applying an identifying coded mark to each structure in the selected positions indicated by the code, and making record thereof, substantially as set forth.

6. The herein described method of charting mechanical structures for individual identification, which consists in selecting and recording a relatively large number of positions 25 for marking such structures, arbitrarily applying a code symbol to each of such positions, selecting keying symbols relating to the code, and making duplicated records of the same, whereby the structures may be 30 marked and identified, substantially as set forth.

7. The herein described method of charting mechanical structures for individual identification, which consists in selecting a 35 relatively large number of positions for marking such structures, recording said posi-

tions in two series, arbitrarily applying a code symbol to each of such positions, selecting keying symbols relating to both series of the code, and making duplicated records of 40 the same, whereby structures thus coded may be given individual marking, substantially as set forth.

8. The herein described method of identifying articles, which consists in charting 45 positions of identification upon said article from which obliteration would be observable, assigning a plurality of such positions to a given article or class of articles, semi-permanently applying an identifying mark in 50 each of the latter positions, and preserving record of the foregoing, whereby an attempted obliteration will result in placing a corresponding series of marks, substantially as set forth.

9. The herein described method of identifying mechanical structures, which consists in selecting and charting a relatively large number of positions of identification upon a typical structure from which obliteration 60 would be noticeable, assigning a smaller number of such positions to the particular structure or structures to be identified, semi-permanently applying an identifying mark to the structure or structures in the last selected 65 positions, and making record thereof, whereby an attempted obliteration will result in further identifying markings, substantially as set forth.

In testimony whereof I do now affix my 70 signature.

JOHN F. GELNAW. [L.S.]
